UNITED STATES PATENT OFFICE.

STEPHEN FAITH AND SAMUEL KLASSTORNER, OF CHICAGO, ILLINOIS, ASSIGNOR TO
FAITH MFG. CO., OF CHICAGO, ILLINOIS, A CORPORATION OF ILLINOIS.

DESIGN FOR AN AUTOMOBILE RADIATOR-CAP ORNAMENT.

Application filed April 11, 1927. Serial No. 21,554. Term of patent 14 years.

To all whom it may concern:

Be it known that we, STEPHEN FAITH and SAMUEL KLASSTORNER, citizens of the United States, residing at Chicago, in the county of Cook, and State of Illinois, have invented a new, original, and ornamental Design for an Automobile Radiator-Cap Ornament, of which the following is a specification, reference being had to the accompanying sheet of drawings, forming part thereof.

In these drawings,
Figure 1 is a front elevational view of our ornament, and

Figure 2 is a side elevational view thereof.
We claim:

The ornamental design for an automobile radiator cap ornament, as shown.

STEPHEN FAITH.
SAMUEL KLASSTORNER.
